E. R. WHITNEY, OF PLATTSBURG, NEW YORK.

Letters Patent No. 77,692, dated May 5, 1868.

IMPROVEMENT IN DUMPING-SLED.

The Schedule referred to in these Letters Patent and making part of the same.

TO ALL WHOM IT MAY CONCERN:

Be it known that I, E. R. WHITNEY, of Plattsburg, in the county of Clinton, and in the State of New York, have invented certain new and useful Improvements in Dumping-Sleds; and do hereby declare that the following is a full, clear, and exact description thereof, reference being had to the accompanying drawings, and the letters of reference marked thereon. In the annexed drawings making a part of this specification—

A represents an ordinary sled, of any suitable size, provided with vertical posts C extending up a suitable distance from about the middle of the opposite sides of the sled A.

The posts C are provided with slots or holes, in which are secured and work pulleys h, as shown in the drawings.

On the top of the sled A, and between the stay-rails or raves thereof, are adjusted movable bars B, which move in suitable ways on the cross-bars of the sled and loops g on the inside of the sled-runners. The bars B are framed together at their forward end by means of a suitable cross-bar, to which power to draw the sled A is attached. Said bars are held in place, and from being drawn out, by means of a simple catch-hook, K, attached to the forward cross-bar of the sled, and hooking into a staple in the cross-piece of the bars B. Adjusted and secured to the hind or back cross-bar of the sled A are pulleys j.

D represents a box or body of suitable dimensions to fit and work between the vertical posts C pivoted to or on the back part of the sled A in any convenient manner, and having a cross-slat secured to its under side in front of the posts C, to which one end of the cord f is fastened. The body D has also in front a suitable loop or staple, which fits and works over the guide or standard E. Said standard E is pivoted to the middle of the forward cross-bar of the sled A, and serves as a guide for the front end of the body D when the same is tipped up or elevated. H represents a spring-catch or brake, which is operated by the foot for the purpose of stopping and holding the sled A from slipping forward while dumping.

A cord, F, is secured to the rear end of the sliding bars B, and passes thence around the pulleys j and up over the pulleys h, and then fastened to the ends of the cross-slat of the body D, as is fully shown. By detaching the hook K, and pressing down on the brake or catch H, the bars B may be drawn forward by the team attached thereto, and the cords F working over the pulleys j and h elevate the front end of the body D, and the load therein is thereby dumped or thrown out. The convenience, simplicity, and economy of this device will be readily seen.

Having thus fully described my invention, what I claim as new, and desire to secure by Letters Patent, is—

1. The sliding bars B, when used in combination with a cord, F, for the purpose of elevating the front part of a body, D, of a sled or wagon, and operated as and for the purpose specified.

2. Operating a dumping-body, D, by means of the same team which draws the same, without detaching and reattaching said team, substantially as and for the purpose specified.

3. The arrangement of the posts C, pulleys h and j, with the cords F, when operated by means of sliding bars B, as and for the purpose herein set forth.

In testimony that I claim the foregoing, I have hereunto set my hand, this 28th day of January, 1868.

E. R. WHITNEY.
